SHOULDER PAD CONSTRUCTION

Helene Pons, New York, N. Y.

Application May 12, 1944, Serial No. 535,251

2 Claims. (Cl. 2—268)

1

This invention relates generally to garments, and especially to an improvement in their shoulder construction.

The prime object of the present invention is the provision of a substantially freely suspended, readily openable pocket permanently secured with its closing seam to the shoulder seam of a garment, the pocket being designed for receiving a removable pad so that when the garment is to be cleaned or washed such pad may be removed to facilitate washing of the garment and reinserted after the garment is cleansed.

Another object of the present invention is the provision of a shoulder pad pocket structure for the purpose above described, wherein the parts of the pockets, preferably made of the same or similar material the garment is made from, are secured to the shoulder seam of the garment to form a bag with overlapping flaps into which a removable pad may be inserted, and wherein the bag or pocket material may be swung to either side of the seam to facilitate ironing of the shoulder garment areas.

These and further objects of the present invention will become more fully apparent from the ensuing description, reference being had to the accompanying drawings forming part of the present disclosure, and in which:

Fig. 1 illustrates a garment equipped with pad receiving shoulder pockets;

Fig. 1a is an enlarged, fragmental, cross section through a pad pocket secured to the shoulder structure;

Fig. 2 is a plan view of one-half of the pocket construction;

Fig. 3 is a plan view of two overlying halves of the pocket structure;

Fig. 4 is an interior plan view of the shoulder portion of the garment to which is secured the pocket structure in its finished form with the pad inserted;

Fig. 5 illustrates a similar view as Fig. 4 showing the manner of inserting the pad into the pocket;

Fig. 6 is a cross sectional view taken on line 6—6 of Fig. 4; and

Fig. 7 is a cross sectional view taken on line 7—7 of Fig. 4.

Referring now specifically to Figs. 1 and 1a, numeral 10 denotes a garment with raised shoulder portions 11, which are held in their raised position by padded pockets 12. Pad 13 is removable from pocket 12. See Fig. 1a.

The constituents of the pocket construction are best illustrated in Figs. 2 and 3. They con-

2

sist of two sections 14 and 15 which are adapted to cooperate with one another as indicated at 16 in Fig. 3. The sections are composed of overlapping portions or flaps 17, free top portions 18 and attaching portions 19. In sections 14 and 15 are indicated several bending lines, lines 20 between portions 17 and 18, lines 21 between portions 18 and 19, and edge bending lines 22 along the edges of flaps 17. These bending lines indicate where the several portions of sections 14 and 15 are folded against one another preparatory to sewing them into a pocket formation. Edges 18' and 19' are then united at the same time the shoulder seam is made, while edges 19'' and 17' are sewed together to form the broad free end of the pocket.

The finished pocket is clearly illustrated in Figs. 4 and 5 and is substantially triangular in shape. It is designed to accommodate a triangularly shaped pad which may be inserted into the pocket by lifting the upper flap 17, while moving the lower flap 17 aside, as indicated in Fig. 5, and then rearranging the flaps to their normal position shown in Fig. 4.

An important feature of the present invention is the manner in which the pocket is attached to the shoulder structure of the garment. The portion of the sleeve which extends downwards over the shoulder is preferably provided with a box pleat 23, which latter forms a continuation of the shoulder seam 24, clearly seen in Fig. 7. In this figure it will be also observed that the sewed-together edge portions 18' are joined with the inwardly turned edges of the garment shoulder seam. As a result the body of the pad pocket is rendered completely free of the garment material except where it is secured to the shoulder seam thereof. It may be said that the pocket is pivotally suspended along the shoulder seam. This feature is of importance in that in the first place the padded pocket may readily accommodate itself to the shoulder of the wearer and secondly when the padding is removed from the pocket, the pocket body may be swung away from the interior shoulder material for the purpose of pressing the garment after it has been washed or cleaned. In this manner the shoulder portions of the garment may be neatly finished by ironing before the padding is reinserted into the pocket preparatory to making the garment ready for wear.

In observing Figs. 4, 5 and 6, it will be noted that at the wide portion of the pocket, the latter is somewhat boxed at 25 to accommodate the highest portion of the pad intended to be located

over the end of the shoulder. Such "boxing" is made possible by portions 19 of the two pocket section.

In the foregoing I have described a rather specific form of my invention, although it is quite obvious that the desired results of a freely suspended pad pocket may be achieved in many other ways, and that the pocket may be formed first and then secured to the shoulder interior without making use of the shoulder seam as means of suspension. I therefore reserve for myself the right to alter and improve the construction of the device, without departing from the broad principle of my invention as expressed in the annexed claims.

I claim:

1. The combination with the shoulder structure of a garment having a shoulder seam, of a pad pocket associated with the interior seam portion of the structure, said pocket comprising two sections having two overlying portions, two other portions joined edgewise with the shoulder seam, and two end portions joining the overlying portions with the two other portions to form a boxed end.
2. The combination with the shoulder structure of a garment having a shoulder seam, of a shoulder pad container of generally triangular shape having side edges and a base edge positioned at the

armhole, said container having a front portion and a rear portion defining a pocket for receiving padding material, the front portion having a mouth for insertion of said padding material, the rear portion having meeting edges along substantially the longitudinal center line forming extension members, said extension members being secured along the shoulder seam on the inside of the garment, and the side edges of the container being free of connection to the shoulder region of the garment whereby the container may be freely flexed for insertion and removal of padding material.
